UNITED STATES PATENT OFFICE.

RAY S. WILBUR, OF LYNDHURST, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,324,364.

Specification of Letters Patent.

Patented Dec. 9, 1919.

Application filed May 13, 1918. Serial No. 234,346.

To all whom it may concern:

Be it known that I, RAY S. WILBUR, a citizen of the United States, residing at Lyndhurst, in the county of Bergen, State 5 of New Jersey, have invented certain new and useful Improvements in Telephone-Exchange Systems, of which the following is a full, clear, concise, and exact description.

This invention relates to telephone exchange systems and more particularly to those in which trunk circuits are employed in completing connections between telephone switchboards or offices.

In such systems it is desirable to provide 15 signaling means whereby the operators handling the connections are definitely advised as to the answered or unanswered condition of the called telephone station. Especially in systems employing operator-controlled 20 signaling means, it is very desirable that the completing or trunk operator receive an accurate and immediate notification upon the answer of the called station.

It is the object of the present invention 25 to provide an improved system of this character which will be simple and inexpensive and will provide a definite signaling means solely responsive to the answer of the called station and unaffected by changes in the 30 electrical conditions of the trunk circuit incident to the establishment of the telephonic connection.

To attain this object, in accordance with a 35 feature of the invention, a trunk circuit provided with the usual ringing signal controlled by a supervisory relay and adapted to indicate when the called station answers, is associated with means to prevent a premature indication being given by the signaling device due to an incidental momentary 40 operation of the supervisory relay prior to the response of the called station.

The nature of this invention will more 45 fully appear from the following specification and annexed drawing in which the figure shows diagrammatically a trunk circuit embodying the invention and sufficient portions of a line circuit and of a link circuit for coöperation therewith, to properly illustrate the operation of the system.

In the accompanying drawing, a trunk 50 circuit D interconnects the switchboards or offices B and C, terminating at office B in a plug 5 and at office C in a jack 14. An ordinary line circuit A equipped with the usual

line relay 3, cutoff relay 2 and line signal 4 terminates in a jack 1 at office B. A connecting or link circuit E of any usual type is provided at office C and terminates in a plug 15 for connection with jack 14 of the 60 trunk circuit D. The portions of the link circuit E (not shown), have been omitted since they are unessential to a proper understanding of the invention.

It is thought that the invention may be 65 more fully comprehended from the following description of the operation of the system.

Assuming that the operator at switchboard C desires to call station A on the line 70 terminating in jack 1 at station B, the operator at B is notified in some suitable manner over a call circuit or otherwise and assigns trunk circuit D. The operator at C thereupon inserts plug 15 of the link circuit 75 E in the jack 14 of the trunk circuit D. The lamp 17 is lighted over a circuit extending from battery through the lamp 17, the resistance 16 and the sleeve contacts of plug 15 and jack 14 to ground. Relay 13 is also 80 operated over a circuit extending from battery through the winding of relay 19, the ring contacts of plug 15 and jack 14, the right-hand winding of relay 13, the tip contacts of jack 14 and plug 15 to ground. 85 However, due to the high resistance of the right-hand winding of relay 13, the supervisory relay 19 of link circuit E is not operated at this time. The operation of relay 13 causes the lighting of the ringing and 90 guard lamp 12 over a circuit established from battery through the lamp 12, the right-hand normal contact of relay 7 and the alternate contact of relay 13 to ground. Relay 8 is also operated over a circuit established 95 from battery through the resistance 21, the winding of relay 8 and the alternate contact of relay 13 to ground. The operator at switchboard B thereupon inserts plug 5 in jack 1 of line A, completing a circuit 100 extending from battery through the winding of relay 9, the sleeve contacts of plug 5 and jack 1 and the winding of cutoff relay 2 to ground. The operation of relay 2 thereupon removes the line relay 3 and its associated 105 line signal 4 from their normal association with the line circuit A. The relay 9 also operates, establishing the continuity of the tip conductor of the trunk circuit, but due to the operation of relay 13 and of relay 8 110

no further useful function is performed thereby at this time.

The operator at switchboard B then actuates the ringing key 10 in the usual manner, impressing signaling current upon the conductors of the line A to cause the operation of the usual signaling device at the called station. The ringing key 10 being released after the signal at the station on the line A has been operated, the trunk circuit apparatus is then in condition to respond to the answer of the called station. Upon the answer of the called station, the supervisory relay 6 is operated over a circuit extending from battery through the winding of relay 6, the lower normal contact of ringing key 10, the ring conductors of plug 5 and jack 1 through the apparatus at the called station, the tip conductors of jack 1 and plug 5, the upper normal contact of ringing key 10, and the upper alternate contact of relay 9 to ground. In operating, relay 6 completes a shunt circuit for relay 8 including the left-hand normal contact of relay 7, the contact of relay 6, and the middle normal contact of relay 7. Due to the presence of this shunt circuit, relay 8 releases, thereby completing a circuit from battery through the lower alternate contact of relay 9, the winding of relay 7, the contact of relay 8, the contact of relay 6, the middle normal contact of relay 7 and the alternate contact of relay 13 to ground. Relay 7 thereupon operates and by the opening of its right-hand normal contact extinguishes lamp 12. A locking circuit is also established for relay 7 extending from battery through the lower alternate contact of relay 9, the winding and the right-hand alternate contact of relay 7, the alternate contact of relay 13 to ground. Through the closure of its middle and left-hand alternate contacts, relay 7 also places the left-hand winding of relay 13 in parallel with the right-hand winding thereof in the usual manner, thus reducing the resistance of the circuit including the supervisory relay 19 of the link circuit E. The consequent operation of relay 19 establishes the usual shunt circuit through resistance 18, around the lamp 17, thereby causing the extinguishment of such lamp. The operator at switchboard C may now converse with the station A upon the actuation of the usual listening key 20. Upon the completion of the conversation, the operator at switchboard C removes the plug 15 from the jack 14, thereby restoring the apparatus associated with the link circuit E to its normal condition and releasing relay 13 to cause the display of the disconnect lamp 11 at the switchboard B, over a circuit established from battery through the middle alternate contact of relay 9, the lamp 11, and the normal contact 65 of relay 13 to ground. Upon observing the

lighted condition of lamp 11, the operator at switchboard B removes plug 5 from jack 1, thereby restoring all apparatus to normal condition.

During the signaling of the called station, the condenser 22 and the conductors of the line become charged and upon the release of the ringing key 10, a discharge may take place through the winding of relay 6, causing the momentary operation of such relay. 75 However, the relay 8 is adapted to be unaffected by any incidental momentary establishment of the shunt circuit therearound and will release only upon a shunt circuit of considerable duration. Therefore, the 80 circuit of relay 7 is not completed due to any incidental operation of the relay 6 caused by the discharge of the capacitance of the line A and the ringing signal lamp 12 is not prematurely extinguished thereby. 85

What is claimed is:

1. In a telephone exchange system, a line circuit having capacitance, a station associated therewith adapted to be called, a trunk circuit for connection therewith, a supervisory relay for the trunk circuit adapted to operate upon the answer of the called station when the trunk circuit is connected with the line circuit, a signal control relay, a relay closing the circuit thereof upon its release, and means operative upon the discharge of the capacitance over the trunk circuit to cause a momentary short-circuiting of the winding of the last mentioned relay, said relay being unaffected thereby.

2. In a telephone exchange system, a line circuit, a station associated therewith adapted to be called, a trunk circuit for connection with the line circuit, a supervisory relay 105 for the trunk circuit adapted to operate upon the response of the called station, a signal control relay, a slow-release relay energized prior to the response of a called station adapted to complete an energizing 110 circuit for the signal control relay when released, and means effective upon any incidental premature operation of the supervisory relay to establish a temporary short circuit around the winding of the slow-release 115 relay of insufficient duration to effect the release thereof.

3. In a telephone exchange system, a line circuit, a station associated therewith adapted to be called, a trunk circuit for connection with the line circuit, a relay operating upon the connection of the trunk circuit with the line circuit, another relay operating prior to the response of the called station, a supervisory relay operating upon the response of the called station to release the second mentioned relay by completing a short circuit therearound, and a signal control relay jointly controlled by the above mentioned relays. 13

4. In a telephone exchange system, a line circuit, a station associated therewith adapted to be called, a trunk circuit for connection with the line circuit, a relay operating prior to the response of the called station, a supervisory relay responsive to the answer of the called station to establish a shunt around and thereby release the first mentioned relay, a signal control relay operating upon the release of the first mentioned relay, and a locking circuit for the signal control relay completed upon the operation thereof.
5. In a telephone exchange system, a line circuit, a station associated therewith adapted to be called, a trunk circuit for connection with the line circuit, a first relay operating upon the connection of the trunk circuit with the line circuit, a second relay operating independently of the connection of the trunk circuit with the line circuit, a signal control relay, an energizing circuit therefore completed upon the contemporaneous energization of the first relay and the release of the second relay, and a supervisory relay responsive to the answer of the called station to establish a shunt around and thereby release the second relay by establishing a shunt therearound and operating the signal control relay.
6. In a telephone exchange system, a line circuit, a station associated therewith adapted to be called, a trunk circuit for connection with the line circuit, a trunk relay operated by current from the distant end of the trunk, a slow-release relay controlled thereby, a sleeve relay operating upon the connection of the trunk circuit with the line circuit, a signal control relay operating upon the contemporaneous operation of the sleeve relay and the release of the slow-release relay, and a supervisory relay responsive to the answer of the called station to establish a short circuit around the slow-release relay of sufficient duration to cause its release.

In witness whereof, I hereunto subscribe my name this 9th day of May, A. D., 1918.

RAY S. WILBUR.
